ABSTRACT OF THE DISCLOSURE

A composition for permanently curling, waving or uncurling hair and keratinic fibres containing thioglycolic or thiolactic acid, or an ammonium salt or an alkali metal salt of these acids, and also an alkalinizing agent, which includes as the alkalinizing agent the carbonate of an alkali metal salt of an amino acid instead of ammonia, said carbonate being free of the various inconveniences characterizing the use of ammonia during the application of said products.

BACKGROUND OF THE INVENTION

It is now conventional to utilize an aqueous solution of thioglycolic or thiolactic acid, or an ammonium salt or an alkali metal salt of these acids, for permanently waving human hair. These aqueous solutions are generally referred to as "cold permanent solutions." These solutions consist essentially of 3% to 8% of thioglycolic acid or thiolactic acid, mostly in the form of the ammonium salt or the alkali metal salt (these proportions having given the best results and meeting maximum safety requirements), and an ammonia excess constituting an alkaline reserve. The pH value of these solutions ranges from about 8.5 to about 10 according to the specific formula employed, and according as the ammonia is converted or not. In addition to these products, which are essential for obtaining the desired effect, the solutions comprise additives adapted to improve the technical properties and the facility of use. These additives are sequestrants, and miscellaneous softeners, such as animal oils, vegetable oils, lanolin derivatives, perfumes, dyes, etc.

It is also known that these solutions can be employed as such for uncurling hair.

For waving hair, the hair impregnated with the product are kept curled on cylindrical curlers during the time necessary for enabling the product to perform its action, this time being selected as a function of the desired degree of curling; in contrast thereto, for the uncurling operation the hair impregnated with the product is drawn or tensioned by combing, or flattened by hand or by brushing, and subsequently pressed on the head in this drawn or extended condition.

More particularly, the uncurling method consists in impregnating the hair to be uncurred with solutions of which the force-denoting number may be selected as a function of the specific characteristics of the hair to be treated, and notably its degree of curling or waving. The hair is soaked with the solution, then combed or flattened or smoothed out so as to press the hair and remove the natural curling therefrom. The hair must be maintained in this "pressed" condition during the application time. When the hairdresser deems that this time has elapsed, after a light rinsing step adapted to remove the greater part of the product, an oxidizing solution adapted to reconstitute the normal texture of the capillary fibre is applied to the hair, with the same procedure as normally employed in a permanent waving operation.

2

However, very fluid solutions having a viscosity approaching that of water are not ideally suited for performing the uncurling operation, for they are generally unable, due to their insufficient viscosity, to keep the naturally curled hair in an extended or drawn condition, especially during the first period of the application time; the natural resiliency of very curled hair is sufficient for reconstituting the natural waves, or the crimped appearance and condition in the case of African hair, in spite of the combining and smoothing steps. The smoothing step becomes gradually more detrimental to the hair as the application time proceeds, for as a consequence of the disorganization of its structure the tensile strength of the hair decreases considerably and thus the combing or smoothing operation may cause more or less important local breakages if care is not taken to avoid this operation when about one-half of the application time has elapsed.

To avoid this danger it is known to apply the reducing uncurling solution in the form of a cream having a consistency sufficient to withstand the resilient action of natural curling which tends inherently to resume its initial shape. Therefore, relatively thick emulsions are used which have a cream consistency and contain to this end an emulsion base of a type known per se. It is obvious that the viscosity of these emulsions may range from the "milk" grade to a pasty one, the technological adaptation alone determining the choice of the viscosity and therefore the proper formulation. These emulsions or creams contain as a rule, like most permanent wave solutions, from 3% to 8% of thioglycolic or thiolactic acid, or of an ammonium salt or of an alkali metal salt of these acids.

Although these products, solutions, emulsions or creams for waving or uncurling hair give satisfactory and sufficient results from the technical standpoint, they are on the other hand unpleasant to handle, mainly on account of their offensive and suffocating smell. In fact, during the storage of these products, solutions, etc. very bad-smelling mercaptans develop and the perfumes utilized for concealing the smell of these products are either destroyed or degraded, at least partially, by reduction and sulfuration, so that their odor is modified and frequently becomes nauseous.

During laboratory research work accomplished by the Applicant with a view to eliminate the inconveniences encountered in the practical use of these products, it was found that free ammonia was responsible for most of these inconveniences. In fact, when released the very volatile and suffocating ammonia carries along the offensive smells of mercaptans. This explains the fact that both the users of these products and the personnel applying the same feel very strongly this release which eventually invades completely the room where the hair treatment is performed.

SUMMARY OF THE INVENTION

To avoid these serious inconveniences it is the essential object of the present invention to provide novel products for the permanent waving and uncurling of hair and keratinic fibres, which contain thioglycolic acid or thiolactic acid, or an ammonium salt or an alkali metal salt of these acids, which are free of volatile ammonia, as an alkalinizing agent.

In these novel products the excess ammonia is replaced essentially by the carbonate of an alkali metal salt of an aminoacid. The aminoacid consists preferably of glycine or glycocoll (aminoacetic acid) but lysine methionine, tyrosine, glutamic acid, leucine, valine, alanine may also be used to this end. These aminoacids may be used in the racemic form or in the form of one of their optical isomers. The alkali metal salt may be a sodium salt, a potassium salt or a lithium salt.

This aminoacid alkali metal salt carbonate may be associated with an organic base such as morpholine, monoethanolamine, triethanolamine, etc.

The carbonate of the aminoacid alkali metal salt, such as sodium glycinate, is adapted to alkalize the curling or uncurling product without having the inconveniences of ammonia; in fact it is not volatile and eliminates the release of unpleasant and suffocating odors, does not attack or modify the perfumes added to said product and is less noxious to the user's skin and to the skin of the person undergoing the treatment.

Other advantageous features characterizing the product of this invention is that it permits of accelerating, by heat effect, the curling or uncurling procedure and thus improves the curling or crimping treatment, without impairing the necessary alkalinity of the product implemented therefor; now it is known that ammonia is highly volatile when heated; therefore, the absence of ammonia eliminates the alteration effects consisting of a reddening of the natural or artificial color of the hair during the curling or uncurling operation, which effects are frequently observed when using conventional products.

Thus, a very substantial improvement is observed from the dual point of view of the operator and of the person receiving the treatment, and the results are also much improved; furthermore, it appears, from practical tests carried out with these products, that in the specific case of hair uncurling a greater safety is obtained against the risk of breaking the hair, as frequently observed with hitherto known processes whenever the treatment is carried out with a certain degree of clumsiness or with certain insufficiencies. Therefore, the results of the uncurling operation are as satisfactory as, and identical if not better than, those obtained with the hitherto applied technique, and the hair is not so ill-treated and emerges from the operation with definitely improved aesthetical properties.

The organic base possibly associated with the aminoacid alkali metal salt carbonate is advantageous in that it makes the hair considerably more pervious to the curling or uncurling product and permits, as a function of its proportion in the product, of graduating the strength thereof, i.e. the degree and rapidity of the curling and uncurling actions obtained with the product.

The proportion of aminoacid alkali metal salt carbonate in the product may advantageously range from about 2 to about 12% by weight, and the proportion of the possible organic base may range preferably from about 1% to about 5% by weight.

The aminoacid alkali metal salt carbonate may be prepared extemporaneously, or even within the curling or uncurling product itself, and in either case without any isolation. This preparation consists in putting into mutual contact, in stoichiometric proportions, alkali metal carbonate and aminoacid, for example 1 mole of sodium carbonate and 2 moles of glycocoll or glycine or aminoacetic acid. From the economical point of view it is advantageous to perform this preparation extemporaneously in aqueous phase during the process of manufacturing the curling or uncurling product.

It will be noted that there is no inconvenience in preparing curling and uncurling products containing an excess either of alkali metal carbonate, or of aminoacid. Thus, the following proportions, for example of sodium carbonate and glycocoll, may be used:

Sodium carbonate	Glycocoll
1 mole	1 mole
1 mole	2.5 moles
1 mole	3 moles
1.5 moles	1 mole
2 moles	1 mole
3 moles	1 mole

The possible excess of one of the components of the aminoacid alkali metal salt carbonate is not included in

the range of percentages by weight given hereinabove for said aminoacid alkali metal salt carbonate.

DESCRIPTION OF THE PREFERRED EMBODIMENTS

Typical examples of formulae for preparing cold permanent waving solutions (Examples 1 to 17) or uncurling emulsions or creams (Examples 18 to 35) according to this invention will now be given. In these examples the percentages are by weight. Moreover, these formulae may include an excess of alkali metal carbonate or aminoacid, although this excess is not mentioned.

EXAMPLE 1

	No. 1	No. 2
Sodium glycinate carbonate, percent	7.4	3.4
50% ammonium or sodium thioglycolate or thiolactate (50% aqueous solution), percent	16	16
Sequestrant (disodium salt of EDTA), percent	0.3	0.3
Methyl p-hydroxybenzoate, percent	0.05	0.05
"Proteol SN," percent	0.2	0.2
Perfume, percent	0.2	0.2
Water (complement to make 100%), pH	8.6	8.3

The function devolved to the sequestrant (disodium salt of ethylenediaminetetraacetic acid) is to complex the calcareous salts contained in water, in order to avoid calcareous deposits on the hair.

Methyl p-hydroxybenzoate is a preservation agent.

"Proteol SN" is a surface-active substance manufactured by the Rhône-Poulenc Company, France, and consists of a protein sulfonation product. This surface active substance improves the wetting capacity of hair and facilitates the penetration of the solution into the hair.

EXAMPLE 2

	No. 1	No. 2
Sodium glycinate carbonate, percent	7.4	3.4
Sodium or ammonium thioglycolate or thiolactate (50% aqueous solution), percent	16.0	16.0
Sequestrant (disodium salt of EDTA), percent	0.3	0.3
Methyl p-hydroxybenzoate, percent	0.05	0.05
"Proteol SN," percent	0.2	0.2
Perfume, percent	0.2	0.2
Morpholine, percent	2.0	2.0
Opaquing agent, percent	0.5	0.5
Water (complement to make 100%), pH	9.0	8.9

The opaquing agent consists of synthetic latex giving a milky appearance to the solution for purely aesthetic reasons.

EXAMPLE 3

	No. 1	No. 2
Sodium glycinate carbonate, percent	7.4	3.4
Sodium or ammonium thioglycolate or thiolactate (50% aqueous solution), percent	16.0	16.0
Sequestrant (disodium salt of EDTA), percent	0.3	0.3
Methyl p-hydroxybenzoate, percent	0.05	0.05
"Proteol SN," percent	0.2	0.2
Perfume, percent	0.2	0.2
Morpholine, percent	2.0	2.0
Opaquing agent, percent	0.5	0.5
Lauryl pyridinium chloride, percent	0.2	0.2
Water (complement to make 100%), pH	9.0	8.9

The function of lauryl pyridinium chloride is to increase the curling rate.

EXAMPLE 4

	No. 1	No. 2	No. 3
Sodium glycinate carbonate, percent	7.4	3.4	5.0
Cetyltrimethylammonium bromide, percent	0.2	0.2	0.2
Sodium or ammonium thioglycolate or thiolactate (50% aqueous solution), percent	16.0	16.0	10.0
Sequestrant (disodium salt of EDTA), percent	0.3	0.3	0.3
Methyl p-hydroxybenzoate, percent	0.05	0.05	0.05
Morpholine, percent	2.0	2.0	2.0
"Proteol SN," percent	0.2	0.2	0.2
Perfume, percent	0.2	0.2	0.2
Opaquing agent, percent	0.5	0.5	0.5
Water (complement to make 100%), pH	9.0	8.9	9.0

5

The cetyltrimethylammonium bromide has the same function as the lauryl pyridinium chloride of Example 3.

EXAMPLE 5

	No. 1	No. 2	No. 3
Sodium glycinate carbonate, percent	7.4	3.4	5.0
"Imidazoline O" (a product of the French company Protex), percent	0.2	0.2	0.2
Sodium or ammonium thioglycolate or thiocrotonate (50% aqueous solution), percent	16.0	16.0	10.0
Sequestrant (disodium salt of EDTA), percent	0.3	0.3	0.3
Methyl p-hydroxybenzoate, percent	0.05	0.05	0.05
Morpholine, percent	2.0	2.0	2.0
"Proteol SN" percent	0.2	0.2	0.2
Perfume, percent	0.2	0.2	0.2
Opacifying agent, percent	0.5	0.5	0.5
Water (complement to make 100%), pH	9.0	8.9	9.0

The product "Imidazoline O" has the same function as the lauryl pyridinium chloride in Example 3. This product is the 1-hydroxyethyl-2-heptadecenyl-imidazoline of formula:

EXAMPLE 6

	No. 1	No. 2	No. 3
Sodium glycinate carbonate, percent	7.4	3.4	5.0
Oxyethylated lanolin, percent	0.2	0.2	0.2
Sodium or ammonium thioglycolate or thioglycolate (50% aqueous solution), percent	16.0	16.0	10.0
Sequestrant (disodium salt of EDTA), percent	0.3	0.3	0.3
Methyl p-hydroxybenzoate, percent	0.05	0.05	0.05
Morpholine, percent	2.0	2.0	2.0

EXAMPLES 10 TO 17

EXAMPLES 18 TO 35

The following Examples 18 to 35 relate to formulae of uncurling emulsions or creams according to this invention. The abbreviation "q.s.p." means "quantity sufficient per." The abbreviation "E.D.T.A." means "ethylenediaminetetraacetic acid," which is a sequestrant. A is the emulsion base, B₁ and B₂ are the alkalizing agents. Sodium methyl p-hydroxybenzoate is a preservation agent. The function of "Imidazoline O" is to improve the uncurling rate.

Of course, various changes may be brought in the details of the above-given formulae, notably in connection with the conventional additives, without inasmuch departing from the basic principle of the invention.

What is claimed is:

1. A composition for permanently curling, waving or uncurling hair and keratinic fibres, comprising 3% to 8% by weight of thioglycolic or thiolactic acid, or of an ammonium salt or an alkali metal salt of these acids, an aqueous carrier and an alkalinizing agent, wherein said alkalinizing agent consists of the carbonate of an amino-acid alkali metal salt, said aminoacid being selected from the group consisting of glycine, lysine, methionine, tyrosine, glutamic acid, leucine, valine and alanine, and said alkali metal being selected from the group consisting of sodium, potassium and lithium, the proportion of said aminoacid alkali metal salt carbonate is within the range of about 2% to about 12% by weight, based on the weight of the composition, and the pH of the composition is in the range of about 8.3 to about 9.3.

2. A composition as set forth in claim 1, which also contains an organic base selected from the group consisting of morpholine, monoethanolamine and triethanolamine, in a proportion within the range of about 1% to about 5% by weight, based on the weight of the composition.

3. A composition as set forth in claim 1, which additionally contains free alkali metal carbonate or free aminoacid.

4. A composition as set forth in claim 1, in the form of an aqueous solution.

5. A composition as set forth in claim 1, in the form of an emulsion.
